Milton Issenberg, Daniel Issenberg, and
Joseph Issenberg, Methuen, Mass.

Application August 8, 1952, Serial No. 20,948

Term of patent 14 years

(Cl. D58—9)

To all whom it may concern:

Be it known that we, Milton Issenberg, Daniel Issenberg, and Joseph Issenberg, all citizens of the United States, residing at Methuen, in the county of Lawrence, and State of Massachusetts, have invented a new, original, and ornamental Design for a Savings Bank Bottle, of which the following is a specification, reference being had to the accompanying drawings, forming a part thereof.

Figure 1 is a front elevational view of a savings bank bottle, showing our new design;

Figure 2 is a side elevational view;

Figure 3 is a top plan view;

Figure 4 is a rear elevational view; and

Figure 5 is a side elevational view rotated 180° from the position shown in Figure 2.

We claim:

The ornamental design for a savings bank bottle, as shown.
